UNITED STATES PATENT OFFICE.

TRAVIS B. MONK, OF CHICAGO, ILLINOIS.

WINDOW-WASHING DEVICE.

Application filed May 13, 1927. Serial No. 190,983.

My invention relates to a window washing device and the object of my invention is to provide a window washing device which is adapted to thoroughly scrub the windows by applying a water covered brush thereto and being combined with means for removing the water from the window, drying the window and preventing any loss of water or dripping during the washing process, or when the washing device is being applied to, or removed from the surface to be washed.

My invention will be best understood by reference to the accompanying drawing forming a part of this specification, and in which,

Figure 1 is a sectional view of a window washing device incorporating my invention.

Figure 2 is a sectional view taken on the line 2—2 of Figure 1.

Figure 3 is a sectional view taken on the line 3—3 of Figure 1.

Figure 4 is a view partly in section of my locking device for holding the cover on the main liquid container.

Figure 5 is an elevational view of that disclosed in Figure 4.

Figure 6 is a rear elevational view of the washing nozzle mechanism incorporated in my invention.

Figure 7 is a front view of that disclosed in Figure 6 and showing some of the gearing embodied therein.

Figure 8 is a top plan view of that disclosed in Figure 6.

Figure 9 is an end view partly in section of that disclosed in Figure 8.

Figure 10 is a horizontal sectional view of that disclosed in Figure 9.

Figure 11 is a sectional view taken in line 11—11 of Figure 10.

Figure 12 is an elevational view partly in section of the washer used in my invention.

Figure 13 is a cross-sectional view of that disclosed in Figure 12.

In the drawing and for the purpose of illustration I have shown the preferred embodiment of my invention in which 10 is any suitable liquid container having an inwardly turning flange 11 on the upper edge thereof and a spout 12 provided on one side. A flexible casing 13 is secured to the end of spout 12 by means of a nut 14 having screw thread engagement with the upper extremity of said spout. On the top of container 10 is provided a cover 15 having an annular lug 16 adapted

to fit within and adjacent the inner edge of the flange 11, as best shown in Figure 4. The cover 15 is provided with an opening 17 for permitting air to be drawn through by the fan 18, which is mounted in the casing 19 for rotation therein. Suitably secured to the upper side of said casing 19 is a motor casting 20 having any suitable form of motor mounted for rotation therein on the shaft 21 on which the fan 18 is also mounted, so that the fan 18 rotates whenever the motor is operated. The casing 19 is provided with a suitable outlet 22, as shown in Figure 1.

Positioned in the bottom of container 10 is a gear pump 23 consisting of two paddle wheels 24 and 27 mounted for rotation within the casing 25. Said casing 25 is provided with inlet openings 26 and an upwardly extending portion 28 which opens into a tubular member 29, leading to the water distributor 30 having openings 31 therein, as shown in Figure 9. The paddle wheel 27 is mounted on shaft 21 and rotates therewith. Said paddle wheel 27 engages paddle wheel 24 and causes the same to rotate with the shaft 32, to which it is secured. On the upper end of shaft 32 is provided any suitable type of universal joint 33 and a shaft 34 extends from said universal joint upwardly through the spout 12 and has a chain 35 secured to the upper end thereof. Said chain 35 is rotated within the flexible casing 36 by means of shaft 34 and the casing 36 extends upwardly through the casing 13 to the head on nozzle mechanism 37, as shown in Figure 9. The upper end of casing 36 is suitably held in place by a bracket member 38 integral with the casing 39. A pinion gear 40 is secured to the upper end of chain 35 and is adapted to rotate therewith and cause the gear wheel 41 to rotate the shaft 42.

Shaft 42 extends lengthwise of the head 37 and is provided adjacent one end thereof with gear wheel 43 and the bevel wheel 44, as best shown in Figure 10. The gear wheel 43 normally meshes with a gear wheel 45 on the shaft 46 and which causes the washer 47 which is mounted on said shaft 46, to rotate therewith. The bevel wheel 44 is normally in mesh with a similar bevel wheel 48 which is mounted on a counter shaft 49 journaled into casing 39, as shown on Figures 10 and 11. The counter shaft 49 has a worm wheel 50 mounted thereon and having engagement with two similar worm gears 51. The worm

gears 51 are integral with the shaft 52 which have soft rubber coverings thereon for forming rollers 53 which are adapted to wipe water from the washed surfaces. Similar 5 rollers 54 engage the rollers 53 and prevent water passing outwardly of the casing on the surface of rollers 53. Plate members 55 are secured by suitable rivets 56 to the casing 39 and said plate members are adapted to engage 10 the rollers 54 to prevent liquid passing out of the casing 39 on the surface of said rollers 54.

The water distributor 30 consists of a tubular member at right angles to the water 15 tube 29 and adapted to communicate with the same through the short tubular member 57 having a manually operated valve 58 therein. Said valve 58 may be of any suitable construction which is adapted to be 20 opened by forcing the plunger 59 downwardly, by means of the hand lever 60, which is mounted on a shaft 61 between lugs 62, as shown in Figures 6 and 9.

The water distributor 30 is provided with 25 a plurality of openings 31 along the front side thereof through which water or other washing liquid may be sprayed onto the rear side of brush 47. Said distributor extends lengthwise of the head 37, approximately the 30 entire length of the brush and rollers, for evenly distributing washing fluid to the surface to be cleaned.

The washer 47 consists of a shaft 63 having a plurality of wires 64, spot welded at points 35 65 along the surface of said shaft 63; between the points where said wire is spot-welded, strips of leather or similar material 66 may be drawn, said leather strips being connected together at the rear side by means of a longitudinal strip 67 being integral with each of the other strips. The strips 66 pass around the shaft 63 more than half way in order that the metallic wires 64 may be practically covered in operation and thereby 45 avoid metallic contact with the surface to be washed.

The head 37 is provided with cap screws 68 and 69 which may be readily removed from their position shown in Figure 10, for 50 the purpose of removing the geared mechanism in that end of the head. The shaft 42 is journaled in cap screw 69 as shown and said shaft may be readily removed through the opening 70, when so desired. The shaft 55 49 and the gearing thereon may likewise be removed through the opening 71 when cap screw 68 is removed.

The lid 15 is provided with hook shaped lugs 73 which are adapted to be engaged by 60 a loop 74 which passes through a lever 75 near one end thereof at the point 76, as shown in Figure 4. Said lever 75 is pivoted on a pin 77 which is suitably secured to a plate member 78. The lower end of lever 75 is provided with a curved portion 79 by which said

lever may be operated for engaging and disengaging said loop 74 with the lug 73. The position of 74 as shown in dotted line in Figure 4 is the normal position taken by said loop when disengaged from lug 73 for permitting the cover 15 to be removed.

The container 19 is provided with an inner cylindrical member 80 seated on the bottom of said container and having openings 81 therethrough for permitting liquid to pass 78 through the same. Within the container 80 is provided a cylindrical screen 82 having its upper end held in position by the lid 15 and its lower end resting on the bottom of said container 10. Within the cylindrical screen 82 is a smaller cylindrical screen 83 having its upper edge flanged over and held in position by the bottom of casing 19 and the cover 15. Between the cylindrical screens 82 and 83 are packed a large number of sponges 84 for straining the liquid out of the mixture of air and liquid as it is drawn downwardly through the spout 12, through the sponges and upwardly through the fan 18 and out into the air through opening 22. A suitable tubular member 85 extends from the inner screen 83 to the outer screen 82 for permitting the water tube 29 and the shaft 34 to pass therethrough without engagement with the sponges.

In the operation of my washing device, the motor positioned in the casing 20 operates the fan 18, which produces a partial vacuum in the container 10, in the casing 13 and in the head member 37, and the shaft 21 operated by the same motor causes the gear pump 23 to force water under pressure upwardly through the tube 29 and through the water distributor 30, and onto the washer 47. The washer 47 is rotated through the medium of shafts 32, 34, chain 35, shaft 42, the gear wheels 43 and 45 and shaft 46. As the washer 47 rotates, the water is brought into contact with the surface to be washed, and as the water passes down over the surface by gravity, the rubber rollers 53 wipe said water from the windows and by the aid of the partial vacuum in the head 37, said water is returned to said head and drawn downwardly through the casing 13 and into the container 10. The cylindrical member 80 is provided with an extension 86 on the front side thereof to prevent said water returning directly from the spout 12 to the fan 18, and requiring said water to pass downwardly through the container and up through the sponges 84 into the cylinder 83, by this time it is practically dry and may be exhausted through the opening 22 of the fan casing without any appreciable loss of water.

While I have described my invention in its preferred form, it is capable of changes without departing from the spirit of the invention. I do not therefore wish to be limited to the precise details of construction set 13.

forth, but desire to avail myself of such changes and modifications as come within the scope of the appended claims.

I claim as my invention:

- 5 1. A window washing device comprising a washer mounted in a nozzle connected to a fluid container; means for spraying washing fluid on said washer; means for rotating said washer; rollers associated with said washer for wiping said washing fluid from the surface being washed and returning said fluid to said nozzle; means for creating a vacuum in said nozzle for aiding the return of said fluid to said nozzle; other rollers associated with the first said rollers for removing washing fluid from the first said rollers and plate members frictionally engaging said other rollers, and fluid straining and absorbing means said fluid straining and absorbing means being incorporated within said fluid container.
- 10 2. A window washing device comprising a washer mounted in a nozzle connected to a fluid container; means for spraying washing fluid on said washer; means for rotating said washer; rollers associated with said washer for wiping said washing fluid from the surface being washed and returning said fluid to said nozzle; means for creating a vacuum in said nozzle for aiding the return of said fluid to said nozzle; means associated with said rollers for removing washing fluid from the same, and fluid straining and absorbing means said fluid straining and absorbing means being incorporated within said fluid container.
- 15 3. A window washing device comprising a washer mounted in a nozzle connected to a fluid container; means for supplying washing fluid to said washer; means for rotating said washer; soft rubber rollers associated with said washer for wiping said washing fluid from the surface being washed and returning said fluid to said nozzle; said washer rotating means having gears associated therewith for rotating said rollers; means for creating a vacuum in said nozzle for aiding the return of said fluid to said nozzle; fluid straining and absorbing means and fluid removing means associated with said roller for removing fluid therefrom, and valve means for cutting off said supply of fluid said fluid straining and absorbing means being incorporated within said fluid container.
- 20 4. A window washing device comprising a washer mounted in a nozzle connected to a fluid container; means for spraying washing fluid on said washer; means for rotating said washer; rollers associated with said washer for wiping said washing fluid from the surface being washed and returning said fluid to said nozzle; means for creating a vacuum in said nozzle for aiding the return of said fluid to said nozzle; other rollers associated with the first said rollers for removing washing fluid from the first said rollers and plate members frictionally engaging said other rollers, and fluid straining and absorbing means said fluid straining and absorbing means being incorporated within said fluid container.

25 fluid container; means for supplying washing fluid to said washer; means for rotating said washer; soft rubber rollers associated with said washer for wiping said washing fluid from the surface being washed and returning said fluid to said nozzle; said washer rotating means having gears associated therewith for rotating said rollers; means for creating a vacuum in said nozzle for aiding the return of said fluid to said nozzle; fluid straining and absorbing means and fluid removing means associated with said roller for removing fluid therefrom; valve means for cutting off said supply of fluid; and openings in said nozzle for permitting the removal of said gears from said nozzle said fluid straining and absorbing means being incorporated within said fluid container.

30 5. A window washing device comprising a flexible tubular casing secured to a fluid container at one end and having a nozzle on the other end; a washer rotatably mounted in said nozzle; means passing through said flexible casing for rotating said washer; a fluid supplying means extending from said fluid container and passing through said flexible casing and communicating with means for spraying said fluid on said brush; means associated with said washer for removing said fluid from the surface being washed and means for producing a vacuum in said flexible casing for returning said fluid to said fluid container.

35 6. A window washing device comprising a fluid container, means to absorb and strain fluid in said container together with means for creating a vacuum therein, a flexible tubular casing secured at one end to the fluid container and having a nozzle on the other end, a wiper rotatably actuated and mounted in said nozzle, a fluid supplying means extending from said fluid container and passing through said flexible casing to communicate with and spray liquid on said wiper, means revolvably associated with said wiper for removing fluid from the surface being washed, and means for manually supplying and cutting off the supply of fluid from said nozzle, said removed fluid being returned to said container by means of a pipe to be absorbed and strained within the fluid container, said pipe being connected to the nozzle and to the container.

40 In testimony whereof I have signed my name to this specification.

TRAVIS B. MONK.
